Atty's.

UNITED STATES PATENT OFFICE.

CHARLES MAXWELL SMALL, OF NEW YORK, N. Y.

ELECTRIC SWITCH.

Application filed July 8, 1924. Serial No. 724,798.

To all whom it may concern:

Be it known that I, CHARLES M. SMALL, of New York, in the county of New York and State of New York, a citizen of the United States, have invented certain new and useful Improvements in Electric Switches, of which the following is a specification.

This invention relates to a switch, designed for use with a telephone, radio, or other delicate instrument susceptible to injury by the overcharging of its circuit, but primarily for use in radio.

In installing an instrument of this nature, it is customary to utilize a cold water pipe or radiator within the house as an instrument ground for operating purposes, and a pipe or its equivalent buried in the earth outdoors, and connected with a lightning switch whereby to carry off directly to ground any electrical charges that may accumulate when the instrument is not in operation.

One of the objects of my invention is to provide a single article which will take the place of the usual lightning switch and ground connection therefor, as well as the instrument ground connection.

Another object of this invention is to provide a means of protecting the instrument from any overcharging of the circuit that might occur during operation.

My invention further contemplates a device which may be operated with facility and reliability, and which will comply with all the requirements of the insurance underwriters, and will be extremely simple and compact in construction, inexpensive to manufacture, and capable of being installed without greater difficulty than attends the simple operation of boring a hole through the window frame, passing certain parts therethrough, and securing the base of the switch in position by screws.

In the accompanying drawings forming part of the application, in which similar reference numerals designate like parts throughout the several views:—

Figure 1 is a plan view of the switch showing the wiring arrangement and instrument connections.

Figure 2 is an elevation taken along the line 2—2 of Figure 1, showing in detail the wiring arrangement and connections from the antenna to ground.

Figure 3 is a plan view of a modified form of switch wherein one knife blade is omitted, and

Figure 4 is a detail view in cross section of the plug which connects the switch with the instrument.

Referring more particularly to the drawings, 1 designates a base of porcelain or other suitable insulating material, said base being preferably of rectangular configuration and having suitable screw holes in convenient places for receiving screws or bolts by which it is attached to a suitable support.

Mounted upon the base is a knife switch 2, suitably proportioned for use as a lightning switch, in accordance with insurance underwriters' requirements, and fastened to the base by means of a screw 3 countersunk therein, said switch being adapted to engage the pair of double spring contacts 4, said contacts being likewise secured to the base by means of a countersunk screw 5. A fuse block 6 is secured to the base substantially parallel to the aforementioned switch by means of spring clips 7 and 7'. The clip 7 is connected by suitable wiring with the screw 5 and the clip 7' is connected to a resilient leaf contact 9, the purposes of which will hereinafter appear.

A second knife switch 10 is mounted upon the base at the opposite end thereof from the first mentioned switch 2, the two switches being in alignment. This switch 10 is adapted to normally engage a pair of spring contacts 11, said switch and contacts being fastened to the base by countersunk screws 12 and 13, respectively. The screw 12 is connected by suitable wiring to a socket 8, hereinafter described.

A metallic screw socket 8 is mounted intermediate the ends of the block, said socket being adapted to receive a threaded plug 14. This plug contains a central contact 15 adapted to press upon the spring contact 9, aforementioned, which contact 15 is connected through the plug to a wire 16. A second wire 17 entering the plug is connected to the metallic shell 18 formed around the exterior of the plug, which shell engages the socket 8, as can readily be seen. The wires 16 and 17 extend away from the base and connect with the antenna and ground binding posts, respectively, of a receiving set R.

In using the device, it will be seen that the normal path of the current is from the antenna to the screw 3 through the switch 2, fuse 6, contact 9 to the plug 14 which has 5 been screwed into its socket, thence to the antenna binding post of the instrument, through the instrument to ground by way of the plug 8 and switch 10. As the switch 10 connects to ground connection outside 10 of the building, all inside grounds are avoided.

When the instrument is not in operation the switch 10 is raised and the switch 2 withdrawn from its clip 4 and swung into contact with clip 11, thus affording a direct path for current from the antenna to ground, cutting out the instrument. It is obvious that the switch 2 cannot be swung over until the switch 10 has been opened. Thus it 15 will be seen that a single ground serves the double purpose of an instrument ground and lightning ground, and at the same time there is no possibility of any current damaging the instrument should the ground connections beyond the switch 10 break or become defective, as the instrument is entirely 20 out of the circuit, when not in operation.

Referring to Figure 3, a modified form of the device is disclosed, wherein the switch 30 10 has been removed and the socket 8 is permanently connected direct to the clip 11. This form may be used in localities where it is preferable to use a cold water pipe inside of the building as an instrument ground.

The purpose of the fuse 6 is to prevent injury to the instrument by any overcharging of the circuit during operation, said fuse being designed to protect the instrument in the usual well known manner. When not in 35 operation, all currents are shunted around the instrument by throwing the switch 2 and consequently no damage can be done.

Having thus fully described my invention, what I claim as new and desire to secure by 45 Letters Patent of the United States is:—

1. In a combined lightning arrester and switch, the combination with the antenna of a radio receiving set and a receiver, of a member electrically connected to ground, and 50 a switch for making the sole electrical connection between the antenna and said member when the receiver is inoperative, a second switch independent of said first mentioned switch for making an electrical connection between the receiver and said member when the receiver is operative.

2. In a combined switch and lightning arrester, the combination with the antenna of a radio receiving set and a receiver, of a member electrically connected to ground, a 55 switch adapted to electrically connect the antenna and the receiver, a second switch adapted when closed to electrically connect said member and the receiver, said first mentioned switch being further adapted to elec-

trically connect the antenna with said member when said last mentioned switch is open.

3. In a combined lightning arrester and switch, the combination with the antenna of a radio receiving set and a receiver of a member electrically connected to the ground, and a lever for making and breaking electrical connection between the antenna and the receiver and between the antenna and said member, a second lever for operatively connecting said member with the receiver, said first mentioned lever adapted to make connection with said member when said second lever is in inoperative position.

4. In a combined lightning arrester and switch, the combination with the antenna of a radio receiving set and a receiver of a member electrically connected to the ground, and a lever for making and breaking electrical connection between the antenna and the receiver and between the antenna and said member, a second lever for operatively connecting said member with the receiver, said first mentioned lever adapted to make connection with said member when said second lever is in inoperative position and a fuse mounted in series with the first mentioned lever.

5. A circuit controller to which a plurality of electric circuits may be electrically attached, comprising a base, a plurality of switches, a ground terminal common to said switches, an antenna terminal connected to one switch and a radio receiver terminal connected to the other switch, means whereby both of said switches complete the circuit from the antenna terminal to the ground terminal, and means whereby one only of said switches completes the circuit from the antenna terminal to the ground terminal.

6. A combined switch and lightning arrester having a fusible electrical connection between an antenna and a receiver and an electrical connection between said receiver and the ground; means for breaking said last mentioned connection and other means independent thereof for directly connecting said antenna to the ground.

7. A combined lightning arrester and switch adapted to form an electrical connection between an antenna and a receiver, and between said receiver and the ground; means for breaking said last mentioned connection and other means independent of said means for breaking said first mentioned connection and directly connecting said antenna to the ground.

8. A combined switch and lightning arrester adapted to form an electrical connection between an antenna and a receiver and between said receiver and the ground; means for breaking said last mentioned connection and other means independent thereof for breaking said first mentioned connection and directly connecting said antenna to the

ground, said first mentioned connection being formed in part of fusible material.

9. An article of manufacture, comprising a non-conducting base, switch levers mounted thereon, a threaded socket mounted in the base, a fuse mounted on the base connected between the socket and one lever, a

ground terminal, means including the other of said levers for connecting said socket to said terminal.

In testimony whereof I hereunto affix my signature.

CHARLES MAXWELL SMALL.
